CONVERSION OF HYDROCARBON OILS

Luis de Florez, Pomfret, Conn., and James W. Gray, Port Arthur, Tex., assignors to The Tex-
as Company, New York, N. Y., a corporation of Delaware

Application June 8, 1931, Serial No. 542,974

1. Claim: (Cl. 196—48)

This invention relates to the conversion of high boiling hydrocarbons into low boiling products, such as gasoline and has particular reference to a process wherein the conversion of hydrocarbon oils takes place in a plurality of stages.

5 The invention contemplates a multi-stage process in which hydrocarbon oil is passed successively through a plurality of zones maintained under conversion conditions whereby the oil may be subjected to a series of operations that are 10 regulated to precise conditions for efficient production of the desired product. The invention further contemplates that the zones or stages of treatment are individually controlled so that the oil may be subjected to separate operations 15 such as, distillation, heating, cracking, digestion, fractionation, each stage of operation being controlled independently of any other stage.

More particularly, the invention, for example, may be carried out in a three stage cracking operation, although the invention is not so limited. In a three stage treating system we provide a high temperature high pressure zone, a high pressure digesting zone of slightly lower pressure, and a relatively low pressure low 25 temperature cracking and distilling zone. The high temperature high pressure zone may conveniently take the form of a coil or tubular heater which is individually controlled by firing; the high pressure digestion zone of slightly lower pressure may consist of an enlarged chamber 30 of sufficient size to afford a time factor for the reaction or digestion operation and this zone may be controlled by the regulated introduction of a cooling medium such as cool or preheated charging stock, clean distillate cycle stock or an extraneous material for reaction or combination with the products undergoing digestion; and the relatively low pressure low temperature cracking and distilling zone may comprise a tower for 35 vaporization and fractionating which may be controlled by the degree of pressure reduction or by the amount of reflux condensation therein.

Heretofore, conversion processes of the general type referred to above, have been carried out 45 in a two stage operation, consisting of the first two stages only of those mentioned and the third stage comprising merely a distillation zone. In the conventional two stage operation, control of the reaction chamber may be effected in various ways and for this purpose it has been proposed to use a cooling medium in indirect heat exchange with the oil in the transfer line connecting the heater and reaction chamber. We are aware also that it has been proposed in

a two stage process to introduce a cooling medium directly into the oil in the transfer line or into the reaction chamber. However, our invention is distinguished from processes disclosed heretofore in not only providing a greater 5 number of stages of cracking than the prior methods but also in the process of the invention the application of certain prior methods of regulating the temperature would be impractical for various reasons, especially because of coke deposits. In our process, it will be observed that 10 control of the heating stage must be maintained to supply sufficient heat to the oil and yet avoid coking the tubes, that control of the digestion or reaction zone must be maintained to avoid 15 coke deposits from the accumulation of excess heat therein and yet maintain sufficient heat to promote the reaction and polymerization with a suitable quantity of heat remaining to be carried over to the distillation zone, and that control of the distillation zone must be maintained 20 to produce the desired degree of cracking and to separate the volatile constituents from the residual fraction to serve as cycle stock for further processing.

The result of operating a three stage process is the production of a highly cracked material in the tubes which has anti-knock properties, the polymerization of certain of the cracked materials in the digestion chamber and the formation 30 of the required amount of cycle stock by the cracking in the tower. The advantage of cracking oil in this manner is to conserve heat, since each of the two last stages is supplied with heat already put into the oil; to make an improved 35 gasoline, particularly from an anti-knock point of view; and to reduce the gas loss by polymerization in the intermediate or digestion stage. Other advantages will be observed from the following description of the process and the apparatus.

For the purposes of illustrating the invention, reference will now be made to the drawing wherein an apparatus is shown for conveniently carrying out the invention and comprising an embodiment thereof.

The reference character 1 represents diagrammatically a heater for heating the oil to conversion temperatures. This heater may be any well-known or preferred type in which coils or 50 tubes are located within a furnace for conducting a charge of oil therethrough in a constricted stream while heat is applied thereto by suitable burners.

A transfer line 2 conducts hot oil from the coil 55

or tubes in furnace 1 to a digester 3. The digester is preferably an elongated horizontal drum of large capacity and capable of withstanding high pressures. It is to be understood, however, that other shapes or designs of digesters may be used.

5 A vaporizer 4 is connected to the digester by a line 5 in which is interposed a pressure reducing valve 6. The vaporizer preferably consists of a vertical tower into which the hot oil is introduced near the bottom through the line 5. The 10 vaporizer may be equipped with trays 7 or other convenient means of fractionation so that the evolved vapors may be separated from entrained liquid or high boiling constituents.

15 The fractionator 10 is adapted to receive vapors from the vaporizer 4 through the vapor line 11, communicating therebetween. The fractionator may be any of the usual type of fractionating towers, preferably of the bubble tower design, wherein bubble trays 12 are located at spaced intervals therein, to contact the vapors with reflux liquid to separate a vapor fraction of desired boiling range.

20 A vapor line 15 serves to conduct the fractionated vapors to a condenser coil 16. A line 17 then conducts the condensate and uncondensed gases to a receiver 18 which is equipped with the usual gas release pipe 19 and a liquid draw-off line 20.

25 Referring again to the vaporizer 4, a tar line 25 serves to withdraw the residual oil or tar from the bottom thereof to a tar stripper 26. A line 27 conducts the unvaporized fraction from the tar stripper to a fuel or residual oil storage tank 28. A vapor line 29 conducts the vapor fraction from the stripper to a condenser coil 30. A pump 31 pumps the condensate from the condenser through the line 32 for use as a reflux medium. The line 32 merges with a charge line 33, herein-after referred to, whereby the condensate may be conducted to the vaporizer 4. A by-pass line 35 40 serves to conduct any or all of the condensate from the line 32, if desired, to the fractionator 10 where it enters by one or more branch lines 36 and 37, connected at different elevations to the fractionator.

45 Referring now to the fractionator 10, a reflux line 40, connected to the bottom thereof, serves to withdraw condensate from the body of oil collecting in the bottom of said fractionator. A pump 41, interposed in the line 40, pumps any 50 part or all of the condensate in the line 40, under pressure, back to the heater 1.

55 A charge tank 45 serves to hold a supply of oil to be converted. A line 46, connecting to tank 45, serves to convey the charge to a pump 47 which then forces the charge through the line 32 hereinbefore referred to, either alone or mixed with a desired quantity of distillate from line 32 to the vaporizer 4.

60 Attention is now directed to the means by which we introduce a cooling liquid into the hot oil in the transfer line 2, located between the heater and the digester. A branch line 50, in which is interposed a valve 51, communicates between the clean distillate line 40 and the transfer line 2 to conduct a regulated quantity of the relatively cool oil from the line 40 into the line 2. Also a line 52 in which is interposed valve 53 and a pump 54 serves to conduct a regulated quantity of cool charge stock, if desired, to the 65 hot oil in said transfer line. A line 55, connected to the transfer line 2, serves to conduct an extraneous material for cooling or reaction with the oil such as hydrogen, hydrocarbon gas or oil.

In practicing the invention with an apparatus

such as that just described, the oil to be converted is raised to a conversion temperature in the heater 1 while under a high pressure of the order of 600-1000 pounds per square inch. The temperature of the oil at the outlet of the heater is preferably maintained at around 900°-950° F. but this may vary somewhat. It is proposed that more or less cracking may take place in the heater and the degree of cracking therein may be regulated by the firing to insure sufficient conversion and at the same time the temperature of the oil will be sufficiently high to maintain the desired temperature in the digester.

10 In the digester 3, the hot oil from the heater 1 is maintained at a high temperature for sufficient 15 length of time to provide a suitable time factor for conversion while the oil is passing therethrough. The temperature of the oil in the drum 3 is usually dependent on the quantity of heat carried by the oil from the heater 1 and the heat 20 so transferred to the digester 3 is preferably maintained by heavy insulation of the digester. It is important that the conditions in the digester be quite well regulated and the temperature particularly be with certain limits in order to avoid 25 filling the drum with large deposits of coke. The pressure in the drum 3 is usually about 600 pounds per square inch or above. A satisfactory temperature has been found to be of the order of 30 910° F. or thereabouts.

The products from the drum 3, containing considerable quantity of low boiling oils, are conducted through the line 5 to the vaporizer 4. A reduced superatmospheric pressure near 35 60 to 70 pounds per square inch, is maintained in the vaporizer by the regulation of the pressure reducing valve 6 in the line 5. The low boiling products quickly vaporize as a result of the reduced pressure and a vapor fraction and a residual liquid fraction separate in the vaporizer.

40 The vapors from the vaporizer 4 containing the desired gasoline and heavier constituents suitable for cracking, such as gas oil, pass to the fractionator 10 through line 11. In the fractionator the vapors are dephlegmated to form a vapor 45 fraction of the desired low boiling constituents, such as gasoline, and a liquid fraction comprising a clean distillate recycle stock. The distillate recycle stock accumulates in a body in the bottom of the fractionator from where it is continuously 50 drawn by the pump 41 and forced, entirely or in part, to the heater 1.

55 The residual liquid fraction separating in the vaporizer 4 is drawn off from the bottom thereof to a stripper 26. This stripper is preferably operated in the nature of a flash still, that is, the pressure is preferably reduced as the oil passes through the line 25. The lower boiling products capable of vaporization at the prevailing temperatures and pressures immediately flash into 60 vapor form in the still 26. A heavy residue or fuel oil is drawn off through the line 21 to a storage tank 28. The vapors consisting chiefly of oils of the nature of gas oil are condensed and pumped either back to the vaporizer 4 or to the 65 fractionator 10, or both, where the condensate acts in the nature of a reflux medium. It will be noted, therefore, that the body of clean distillate recycle stock at the bottom of the fractionator may also contain a distillate from the flash 70 still 26.

The fresh charging stock to the system may be drawn from a source of supply such as a tank 45 and pumped into the top of the vaporizer 4. In the vaporizer, the fresh charge comes in con- 75

tact with the hot vapors therein, whereby it is stripped of its lower boiling constituents and at the same time condenses undesirable constituents in the vapors. A conversion temperature of about 700°-850° F. and a pressure of 50-150 pounds per square inch is preferably maintained in the vaporizer 4 and as a result thereof not only may conversion of the oil passing from the digester continue, but also substantial conversion 10 of the fresh charge occur. The unvaporized fresh charge mingles with the hot residual fraction in the vaporizer and eventually passes to the stripper 26. The pressure in the tower 4 may be regulated to control the temperature by causing more 15 or less vaporizing which absorbs heat. Furthermore, the temperature in the vaporizer may be regulated by the amount of cooling effected by the reflux liquid and charging stock introduced through the lines 32 and 33.

20 We will now describe the manner in which we control the temperature of the oil in the digester 3. According to one method of operation a regulated portion of the clean distillate recycle stock may be introduced into the hot oil in the transfer 25 line 2 and for this purpose we have shown the by-pass line 58 between the line 40 and transfer line 2. The recycled stock is relatively cooler than the oil in the transfer line 2, and if extensive cooling is not required the resultant cooling will 30 often regulate sufficiently the temperature of the oil entering the digester.

In another method of operation a part of the cool fresh charging stock may be pumped to the hot oil in the transfer line 2 by passing a regulated quantity through the by-pass line 52. It 35 will be observed that in the ordinary type of operation more extensive cooling may be obtained in this way.

In still another method of operation we may introduce an extraneous material through the line 55. For this purpose a suitable oil may be introduced which will not only cause cooling but also supply hydrogen for hydrogenation or even 5 free hydrogen may be introduced. Furthermore, any of the above methods may be used separately or any or all of them may be operated simultaneously.

Obviously many modifications and variations 10 of the invention as hereinbefore set forth may be made without departing from the spirit and scope thereof, and therefore only such limitations should be imposed as are indicated in the ap- 15 pended claim.

We claim:

The method of cracking hydrocarbon oil, which comprises subjecting the oil to heat and greater than atmospheric pressure in a cracking zone to 20 crack the oil, vaporizing portions of the thus treated oil under reduced pressure greater than atmospheric pressure, washing tarry material from the vapor at said reduced pressure, separately withdrawing the wash liquid containing 25 the tarry material, vaporizing the wash liquid and condensing the vapors whereby the wash liquid is freed from tarry material, removing the tarry material from the system, reusing the liquid to wash additional vapor, condensing a 30 relatively heavy fraction of the washed vapors, passing the condensed heavy fraction to the cracking zone to crack the same together with said hydrocarbon oil, and condensing the remaining washed vapors. 35
